UNITED STATES PATENT OFFICE.

PERCY E. BARKER, OF CLEVELAND, OHIO, ASSIGNOR TO THE VAN DORN IRON WORKS COMPANY, OF CLEVELAND, OHIO, A CORPORATION OF OHIO.

DUMP TRUCK.

Application filed September 14, 1921. Serial No. 500,621.

To all whom it may concern:

Be it known that I, Percy E. Barker, a citizen of the United States, residing at Cleveland, in the county of Cuyahoga and State of Ohio, have invented certain new and useful Improvements in Dump Trucks, of which the following is a specification.

This invention relates to improvements in hoisting mechanism for dump trucks.

10 The objects of this invention are to provide an improved hoisting mechanism for dump trucks in which the truck body has positive connection with the hoisting mechanism and without the use of a cable for 15 raising and lowering the body; to so arrange the hoisting mechanism that the load will be evenly distributed to the different parts of the same and thereby increase its efficiency and lengthen its life; to provide the 20 hoisting mechanism as a unit that can be mounted upon any standard truck chassis; to provide also means for automatically stopping the hoisting mechanism at the upper and lower limits of travel of the truck body.

25 Other objects of the invention will appear from the following description and claims when considered together with the accompanying drawings.

30 Fig. 1 is a side elevation, partly broken away, of my improved dump truck; Fig. 2 is a front end elevation of the operating connections; Fig. 3 is a longitudinal section through the center line of Fig. 4 and shows 35 the operating connections to the hoisting mechanism; Fig. 4 is a view, partly in plan and partly broken away, of the casing which encloses the operating mechanism; Fig. 5 is an enlarged elevation, partly broken away, 40 of the hoisting mechanism assembled as a unit; and Fig. 6 is a plan view of the same.

45 In the general view of my invention as illustrated in Fig. 1 the chassis is indicated by reference numeral 1, the hood by reference numeral 2, and the swinging truck body by the reference numeral 3, it being understood that the hoisting mechanism might be operated by a suitable connection from the engine of the truck or other source 50 of power. The hoisting mechanism which, as illustrated in Figs. 5 and 6, is assembled as a unit and applied as such to the chassis of the truck, is mounted upon the channel bars 4 and 5 which are secured to the chassis by means of the brackets 6. The bars 4

and 5 extend from the back of the driver's seat to a point near the rear end of the chassis, as seen in Fig. 1, and the front brackets 6 extend upwardly beyond the chassis along the sides of the under-frame 60 of the truck body. These channel bars are braced by means of the angle bars 7, 8 and 9 which are secured to the lower webs thereof by means of the plates 7', 8' and 9'. The tie rod 10 extends through the main walls of the channel bars 4 and 5. Fillers of wood are provided along the upper and lower sides of the top and bottom flanges of the channel bars 4 and 5, as indicated at 11, and are secured thereto in any suitable manner 65 as for instance by means of bolts or the like. The casing, indicated in a general way at 12, encloses the operating mechanism for raising and lowering the truck body and is afforded support at its forward portion by 70 means of the brace bar 9. As indicated in Fig. 3, the rear middle portion of the casing 12 is provided with a recess in its under face to allow clearance for the differential or the drive mechanism of the truck. As 75 above stated, any suitable source of power may be employed for driving the shaft 14 and in the present case the sprocket 15 is shown as being mounted upon the front end of the shaft 14 for operation by a chain 80 which in turn may be driven from the engine of the truck. As 85

Splined upon the shaft 14 is the clutch member 16 which is adapted to be slid into and out of clutching engagement with the 90 companion clutch members 17 and 18 which are fixed upon the shaft 14. The clutch member 17 carries the gear 19 which meshes with the gear 20 fixed upon the shaft 21 extending through the casing and which also 95 carries the worm 22 meshing with the worm gear 23. Pinion gears 23^a mounted upon the shaft 24 mesh in turn with two gears 25 keyed to sleeves 27^a carrying pinions 27 and mounted on shaft 26 upon the opposite 100 ends thereof. These two pinions 27 mesh with the gears 28 which are fixed upon the aligned but separate shafts 29. The shafts 29 have bearing support at their outer ends in the bearing blocks 30 mounted upon the 105 inside of the channel bars 4 and 5 as part of the drive mechanism unit. Fig. 4 shows only one-half of the mechanism enclosed within the casing, but it will be understood that the structure of the pinions 27, the two 110

shafts 29 and the gears carried thereby as well as the bearings therefor are alike. The purpose of this particular arrangement of aligned, separate shafts will appear later. 5 The cover plate 32 is provided for the opening through the top of the casing 12 and other suitable openings are also provided to permit access to the inside thereof. It will be understood that suitable means of mounting the several gears and shafts within the casing are also provided. With the drive connection just now described it will be seen that the shaft 14 will communicate driving motion from its gear 19 to gear 20, that is 10 when the clutch member 16 is thrown into engagement with the clutch member 17. Through the meshing gears and pinions described, motion will be transmitted to the two aligned shafts 29 upon which are 15 fixedly mounted the crank arms 33 which in turn are pivotally connected with the lever arms 34. The arms 34 are mounted at their other ends to turn on a suitable shaft 35 mounted in the under-frame 36 of the 20 truck body. As clearly shown in the drawings, the lever 34 has an angular form, the upper end portion 34^a extending at approximately 90° to the truck body throughout practically all stages of the hoisting and 25 lowering operations.

With this arrangement, operation of the shaft 29 causes a swinging upward movement of the truck body which is pivotally mounted at 37 in the bearing supports 38 fixed to the inside of the main walls of the channel bars 4 and 5, at the rear ends thereof. The clutch 16 is controlled by means of the yoke member 40 carried by the rod which is reciprocated back and forth by 35 means of its connection 42 with the operating rod 43 which in turn has sliding movement through the casing. This clutch control mechanism is actuated by the operator from the front end thereof by any 40 suitable lever connection, as for instance indicated at 45. The rod 43 carries a stop member 46 which is adapted to be engaged by the companion trip members 47 carried upon one face of the gear 28. This particular mechanism is for the purpose of 45 automatically shifting the clutch member 16 from engagement with either of the companion-clutch members 17 or 18 into neutral position so as to automatically stop the 50 swinging movement of the truck body when it has reached its upper or lower limit of movement. The clutch member 16 is shown in Fig. 3 as occupying neutral position.

When the clutch member 16 is moved into 55 engagement with the clutch member 18 the pinion 50 carried thereby is set into operation and transmits its motion to the meshing pinion 51 which in turn drives the meshing pinion 52 fixed upon the shaft 21. It 60 will be understood that the additional or

intermediate pinion in this particular gear combination effects a reversal of the direction of operation of the shaft 21 from that which is obtained when the drive is through the pinions 19 and 20. Thus it will be clear 70 that the engagement of the clutch member 16 with the clutch members 17 and 18 will effect driving of the shaft 21 in either one direction or the other.

From the above it will be seen that in 75 order to raise the truck body the operator will actuate the lever 45 in the proper direction to bring the clutch member 16 into engagement with clutch member 17, whereupon the shafts 29 are set into operation. 80 The crank arms 33 then move about the axis of the shafts 29 and the truck body is raised to the position of approximately 45° to the horizontal, as indicated in dotted lines in Figs. 1 and 5, the truck body being pivoted 85 at a point near its rear end. The operator may disconnect the clutch at any time by means of the lever 45 so as to stop the raising movement of the truck body or he may depend upon the means for automatically 90 throwing the clutch member 16 into neutral position to thereby stop the swinging movement. When it is desired to lower the truck body, the clutch member 16 is moved into engagement with the other companion clutch 95 member so as to operate the shafts 29 and cause the lever arms 33 and 34 to fold below the same, as illustrated in full lines in Figs. 1 and 5. The operator may at any time 100 throw the clutch into neutral position so as to stop the truck body at any degree of inclination desired or he may depend upon the automatic means for throwing out the clutch at its lower limit of movement.

With the present structure, the hoisting mechanism is assembled as a unit and the particular form of hoisting mechanism including the folding levers contributes to the compactness, simplicity and efficiency of the device. Another advantage resides in the 110 provision of aligned shafts, with separate lever connections to the truck body, which arrangement distributes the load to both sets of levers and precludes the possibility of one set of levers carrying the entire load as 115 might otherwise be the case.

Other advantages flowing from this invention will readily suggest themselves to those who are familiar with the art to which it relates. 120

What I claim is:

1. Dumping apparatus comprising a supporting frame, a dumping body mounted on said frame for raising and lowering movement, and hoisting means comprising separate sets of lever mechanism, an operating connection for each set of lever mechanism, and a single operating means for said operating connections for said lever mechanisms, said parts being so constructed and arranged 125 130

that the separate sets of lever mechanism are individually responsive to the load.

2. Dumping apparatus comprising a supporting frame, a dumping body mounted on said frame for raising and lowering movement, and hoisting means comprising separate sets of lever mechanism, shafts individually responsive to the load for operating said lever mechanisms, a driving connection for each of said shafts, and means for operating said driving connections to thereby operate said lever mechanisms.

3. Dumping apparatus comprising a supporting frame, a dumping body mounted on said frame for raising and lowering movement, and hoisting means comprising separate sets of lever mechanism arranged on opposite sides of the longitudinal middle line of the dumping body for operating said body, shafts individually responsive to the load for operating said lever mechanisms, a driving connection for each of said shafts, and means for operating said driving connections to thereby operate said lever mechanisms.

25

4. Dumping apparatus comprising a supporting frame, a dumping body mounted on said frame for raising and lowering movement, and hoisting means comprising aligned shafts mounted in said frame and having their adjacent ends free, separate sets of lever mechanism connecting said shafts and dumping body, a driving connection for each of said shafts and means for simultaneously operating said driving connections to thereby operate said lever mechanisms.

5. In a device of the class described, hoisting mechanism comprising duplicate aligned shafts having their adjacent ends free, duplicate sets of lever mechanism connected at one end to the outer end portions of said shafts, duplicate driving connections for said shafts, and means for simultaneously operating said driving connections so as to operate said lever mechanism.

In testimony whereof I hereby affix my signature.

PERCY E. BARKER.
